W. D. MOON.

SAFETY STOP FOR MINE CARS.
APPLICATION FILED DEC. 2, 1916.

1,217,620.

Patented Feb. 27, 1917.

UNITED STATES PATENT OFFICE.

WILLIAM D. MOON, OF BLOCTON, ALABAMA, ASSIGNOR OF ONE-HALF TO CLYDE W. LOWREY, OF BLOCTON, ALABAMA.

SAFETY-STOP FOR MINE-CARS.

1,217,620.

Specification of Letters Patent. Patented Feb. 27, 1917.

Application filed December 2, 1916. Serial No. 134,644.

To all whom it may concern:

Be it known that I, WILLIAM D. MOON, a citizen of the United States, residing at Blocton, in the county of Bibb and State of Alabama, have invented certain new and useful Improvements in Safety-Stops for Mine-Cars, of which the following is a specification, reference being had to the accompanying drawings.

10 This invention relates to improvements in safety devices for mine cars or cars moving upon inclined surfaces and the object of the invention is to provide means whereby the car may be stopped or derailed when upon an incline and if the hoisting cable breaks or for any other reason the car moves backward.

20 A further object of the invention is to provide drag bars adapted to be detachably mounted upon the draw bar of the car so that the drag bar attachment may be shifted to the rear end of the car or the last car of a train of cars.

25 A further object is to provide an attachment of this character wherein the drag bars cannot get under the car in case of a wreck and in which the drag bars are so formed that they can never rise too high nor extend out too far to either side.

30 A further object is to provide a construction of this character in which the drag bars will straddle the usual rollers on which the cable is supported so as not to foul the cable.

35 Other objects will appear in the course of the following description.

My invention is illustrated in the accompanying drawings, wherein—

Figure 1 is a plan view showing my drag bar applied to a mining car;

40 Fig. 2 is a side elevation of the structure shown in Fig. 1;

Fig. 3 is a longitudinal sectional view through a portion of the draw bar and through the socket member 10; and

45 Fig. 4 is a section on the line 4—4 of Fig. 3.

Referring to these figures A designates the ordinary track upon which the cars are supposed to run, this track being at an incline.

50 The track is supported upon the usual ties B carrying the usual rollers C. All of these parts are ordinarily found in tram roads for mines. Operating upon the rails A is the car D or train of cars. Each of the cars D is provided with the usual draw bar E.

My invention consists of a rectangular casing 10 which is open at opposite ends and is adapted at one end to fit over the draw bar E and be held in place thereon by the pin 11 which passes through perforations in the upper and lower walls of the casing 10. The side walls of the casing 10 are formed with openings for the passage of a transverse pivot pin 12 and pivotally mounted upon this pivot pin 12 are the drag bars 13. These bars extend outward and laterally at a sufficient inclination to a vertical plane passing through the axis of the cars so that the extremities of the bars will not strike the rollers C but will travel on each side of these 70 rollers. The under face of the casing 10 at its rear end is cut away as at 14, the purpose of which is to allow the drag bars to incline downward at a proper angle so as to ride over the ties. Inasmuch as the casing 10 projects beyond the forward edge of the cut away portion 14, it is obvious that the drag bars will be prevented from rising too high and that the side walls of the casing prevent the drag bars from spreading too much. 80

The box or casing 10 is made of material which may be bent and the drag bars may also be bent and in this way the device may be made adjustable to any height of car. The drag bars 13 are always dragged lightly 85 over the surface of the ties and can never get too high or too far out to either side. The ends of the drag bars travel laterally of the outer ends of the rollers C but inside of the rails. 90

With a drag constructed in accordance with this invention, the drag bars can never get under the car in case of wreck because the box or casing 10 will only permit the drag bars to be depressed to a certain angle 95 and further than this they cannot move unless something breaks. The drag, as it is obvious from the drawings, is at all times in place to do its work and cannot get out of place. It will not knock the rollers C out of position and permits the drag rope or cable by which the car is moved to travel on the rollers and this keeps the rope from dragging on the ties. 100

Immediately upon the trip breaking and the car starting to run backward down the slope, this drag will either stop the cars on the rails or derail the rear car to which it is attached and the derailed rear car will stop all the remainder of the cars of the train 110

and keep them from being broken up, keep the timbers of the mine from being knocked out, and prevent casualties to the men and mules.

5 It will be seen that my attachment may be readily removed from one car and placed upon another and that it may be readily removed when the car is moving down a slope. Of course it is obvious that the drag bars may 10 be made as heavy as desired but they should not be of greater strength than the draw bar.

It will be seen from the drawings that the drag bars 13 are slightly curved downward with points beveled or made sharp so 15 that they will easily stick either in wood or dirt. It will be seen that the drag bars will not come in contact with the rollers C not only because the drag bars are spaced at their rear ends a distance greater than the 20 length of the rails but for the reason that the drag bars will pass over anything that the car axles will.

Having described my invention, what I claim is:

25 1. A safety attachment for mining cars comprising a casing adapted to receive and engage with the rear end of a draw bar, and a drag bar pivotally mounted in the rear end of the casing.

30 2. A safety attachment for mining cars comprising a socket member adapted to fit over the end of a draw bar and be detachably connected therewith, and rearwardly divergent drag bars pivotally mounted for 35 vertical movement in the other end of the socket member.

3. A safety attachment for mining cars comprising a socket member adapted to fit over the end of a draw bar and be detach-

ably connected therewith, and rearwardly 40 divergent drag bars pivotally mounted for vertical movement in the other end of the socket member, the under side of the socket member being cut away at its rear end to permit the drag bars to extend downward 45 and rearward, the top of the socket member preventing too great upward movement of the drag bars.

4. A safety attachment for mining cars comprising a socket member adapted to be 50 disposed over the end of a draw bar and detachably connected therewith, and rearwardly divergent drag bars pivotally mounted in the rear end of the socket member for independent vertical movement.

5. A safety attachment for mining cars comprising a socket member rectangular in cross section and relatively shallow and adapted to be disposed over and engaged with the rear end of a draw bar, the socket 60 member having perforations in its upper and lower walls for the reception of an attaching pin to the draw bar, the bottom of the socket member at its rear end being cut away so as to be shorter than the top and the side walls of the socket member at its 65 rear end being perforated, a pivot pin passing through the last named perforations, and divergently disposed drag bars pivoted upon said pin and having limited vertical movement within the socket member.

In testimony whereof I hereunto affix my signature in the presence of two witnesses.

WILLIAM D. MOON.

Witnesses:

C. W. McCool,
VASIL STANOFF.
